UNITED STATES PATENT OFFICE.

CLYDE S. PELTON, OF CLEVELAND HEIGHTS, OHIO, ASSIGNEE, BY MESNE ASSIGNMENTS, TO THE STANDARD PARTS COMPANY, OF CLEVELAND, OHIO, A CORPORATION OF OHIO.

HEATER FOR MOTOR-DRIVEN VEHICLES.

1,302,208.

Specification of Letters Patent. Patented Apr. 29, 1919.

Application filed February 5, 1916. Serial No. 76,336.

To all whom it may concern:

Be it known that I, CLYDE S. PELTON, a citizen of the United States, residing at Cleveland Heights, in the county of Cuyahoga and State of Ohio, have invented a certain new and useful Improvement in Heaters for Motor-Driven Vehicles, of which the following is a full, clear, and exact description, reference being had to the accompanying drawings.

This invention relates to heating appliances whereby the exhaust gases from internal combustion engines may be used for heating purposes without the creation of noise or interfering with the operation of the engine or producing unpleasant odors within the space to be heated. The device in question while originally designed and peculiarly adapted for heating vehicles driven by gasolene engines may be employed in any place where internal combustion engines are employed. The particular type of heater here disclosed has been produced for the purpose of heating florists' cars, ambulances, omnibuses, delivery wagons and other vehicles of a commercial type. The objects of the invention are the provision of a heating device light in weight, simple in construction and inexpensive in manufacture, efficient in heat transfer, easy to clean when necessary, having a large air contact surface combined with a small floor area, and not liable to get out of order. Other objects and advantages will appear as the description proceeds.

Generally speaking my invention may be defined as consisting of the combinations and constructions recited in the claims hereto annexed and illustrated in one embodiment in the drawings accompanying and forming a part of this application, wherein Figure 1 is a side elevation of a commercial vehicle equipped with a heater of my invention, portions of the vehicle being broken away to show the mode of installing the heater; Fig. 2 is a vertical longitudinal sectional view through the heater showing its interior construction; Fig. 3 is a transverse vertical section on the line 3-3 of Fig. 2; Fig. 4 is a plan view of the exhaust pipe connection showing the mode of regulating the heat; Fig. 5 is a sectional view through the exhaust pipe and controlling valve; Fig. 6 is a perspective view of the exhaust fitting preferably employed with my said heater; and

Fig. 7 is a sectional view showing the silencing strips.

Describing the parts by reference characters 1 represents the exhaust pipe of an internal combustion engine and 2 the muffler ordinarily employed in connection therewith; secured to the side of said pipe between the engine and muffler is a saddle 3 having a hollow neck 4 in which is clamped the branch pipe 5 which is preferably of flexible metallic nature as illustrated. Inside this saddle the exhaust pipe 1 is notched as shown at 6 and journaled in the neck 4 is a rock shaft 7 substantially tangent to the exhaust pipe. Inside the neck 4 this rock shaft carries a valve disk 8 adapted when in one position to close the said branch and when in another position to project a suitable distance into the main exhaust pipe as shown in Fig. 5; outside of said neck the rock shaft carries an operating lever 9 suitably connected by means of a rod or wire 10 to an operating contrivance within the car. The latter, in the present embodiment, comprises an arm 11 carried by a stud 12 pivoted within a sector 13 whereby said lever may be held in fixed position, and such position estimated.

The heater itself comprises a pair of upright headers 15, 16 provided with flanges 17-17 adapted to rest on the car floor and with shanks 18-18 adapted to depend through suitable apertures in the floor. The sides of said headers are formed with apertured ears 19 adapted to receive the bolts 20-20 whereby the inlet and outlet fittings are secured in place and the heater attached to the floor. The inlet fitting comprises an elbow 21 having at one end a clamping socket 22 adapted to receive the branch pipe 5 and having at the other end a base flange 23 provided for the reception of the bolts 20-20. The flanged end of said elbow is also recessed for the reception of the inlet shank 18. Preferably the number of apertures is greater than the number of bolts so that the elbow can be turned in any direction as may be necessitated by the position of the exhaust pipe relative to the rest of the car or to the position of the heater therein.

The adjacent faces of the headers 15, 16 are formed with opposed tapering sockets 24-24 adapted to receive the ends of the heating tubes 25. These tubes are preferably of copper or the like soft heat conducting

material and are drawn forcibly into their sockets by means of tie-rods 26-26. The intermediate parts of said tubes are preferably flattened as shown in Figs. 2 and 3 so 5 as to facilitate the circulation of air between the same, the ends being left circular for convenience of construction. To the exteriors of the headers 15, 16 I preferably secure a perforated metal plate 28 whose upper portion 10 is bent over the tops of the headers and whose lower edges are left free as shown in Fig. 3.

The inlet header 15 is preferably narrowed from its lower toward its upper portion to 15 compensate for the escape of gases laterally therefrom through the tubes 25. The header 16, however, is formed with an interior septum 30 extending from its lower part to a point adjacent its upper end and spaced an 20 increasing distance from the ends of the tubes 25, its inclination being substantially complementary to that of the wall of the upright 15. The space upon the rearward side of the septum 30 is in free communication 25 with the outlet shank 18. The purpose of the septum is to effect a substantially equal distribution to the gases between the different tubes.

The outlet fitting above mentioned consists 30 preferably of a hollow metal body 32 recessed to receive the shank 18 and formed outside of said recess with an apertured flange 33 similar to the flange 23 of the inlet fitting. Projecting laterally from the body 35 is a hollow extension 34 having its bottom side formed at points increasingly distant from the body with a plurality of narrow transverse slots 35. I have also shown the end of the portion 34 as formed with a 40 small outlet aperture 36.

Experience has shown that with the herein described inclination of the upright 15 and the septum 30 the distribution of the exhaust gases to the different pipes 25 will 45 be substantially uniform, the opposition caused by the narrowing of the passage in the inlet header being substantially equalized by the facility produced by the widening of the passage in the outlet header. The 50 high conductivity and radiating effect of the device together with the freedom of air circulation causes such a cooling of the gases therein as to produce a very complete muffling effect, in addition to which the breaking 55 up of the exhaust stream into a plurality of separate streams and then recombining the same further obliterates the exhaust noises. The puffs of gas escaping from the exhaust header are caught in the exhaust fitting 60 and delivered to the atmosphere through the slots 35 in a substantially continuous flow.

However, the thin metal tubes are liable to be thrown into vibration by the exhaust so as to become noisy, wherefore I provide 65 means to damp their vibrations, preferably

by clamping metal strips 40, 40 upon them by means of bolts 41, the strips being lined with asbestos 42 or like cushioning material which shall distribute the pressure upon the various tubes. 70

In the present heater I have produced a device of great simplicity and compactness, wherein the desired muffling effect is secured while maintaining all of the pipes at substantially equal temperatures, thus securing 75 a maximum heating effect with a minimum of leakage and cracking of pipes by unequal expansion. Also the thin metal pipes are peculiarly free from carbon deposit, while such deposit, if found, can be easily removed by disconnecting the heater in a simple and obvious manner. It will be apparent that many changes in detail of construction and arrangement could be made within the scope of my invention and 80 within the intent of the claims annexed hereto.

Having thus described my invention, what I claim is:—

1. In a heater for motor-driven vehicles, 90 a pair of substantially parallel headers having pipe connections at similar ends and having their opposite ends closed, a plurality of parallel tubes connecting said headers, one of said headers having an inclined 95 wall opposite said tubes defining a gradually narrowing chamber and the other header having therein a septum substantially parallel to said inclined wall, one end of said septum being joined to said wall between said pipe connection and the nearest tube, and the remainder of said septum being spaced from the rear wall of said header to form a passageway. 100

2. In a heater for motor-driven vehicles, 105 a pair of parallel headers, a plurality of tubes connecting the same, each of said headers having one end open and having near that end a floor flange, the opposite end of said headers being closed, one of said 110 headers being narrowed from a point near said flange to its closed end and the other of said headers having a septum therein whereby it is narrowed in the opposite direction at a substantially equal rate, and 115 said last header having a passageway therein around said septum.

3. In a heater for motor-driven vehicles, 120 a pair of substantially parallel upright headers, a plurality of parallel tubes connecting said headers the upper of said tubes being spaced from the tops of said headers, and a sheet of perforated metal bent over the tops of said headers and secured thereto the free ends of said metal sheet being bent down to parallelism with said headers and secured thereto whereby the metal sheet is spaced from said tubes. 125

4. In a heater for motor-driven vehicles, 130 a pair of headers, a plurality of parallel

thin metal tubes connecting said headers, and elongated metal strips clamped against said tubes, there being non-combustible cushioning material inserted between said 5 strips and said tubes.

5. In a heater for motor-driven vehicles, a pair of headers, a plurality of parallel thin metal tubes secured to and connecting said

headers and carried thereby, and cushioning and bridging members securely clamped 10 around said tubes intermediate their ends whereby said tubes are prevented from vibrating.

In testimony whereof, I hereunto affix my signature.

CLYDE S. PELTON.
